United States Patent Office.

WILLIAM WESTLAKE, OF CHICAGO, ILLINOIS.

Letters Patent No. 102,895, dated May 10, 1870.

IMPROVEMENT IN LANTERNS.

The Schedule referred to in these Letters Patent and making part of the same.

To all whom it may concern:

Be it known that I, WILLIAM WESTLAKE, of the city of Chicago, in the county of Cook and State of Illinois, have invented certain new and useful Improvements in Lanterns; and I do hereby declare that the following is a full, clear, and exact description thereof, reference being had to the accompanying drawings making a part of this specification, in which—

Figure 1 is an elevation of the completed lantern; Figure 2, a vertical section of the cap detached; Figure 3, a top view of the base; and Figure 4, a vertical section of the base.

Like letters refer to the same parts in all of the figures.

The nature of my invention consists in forming a pressure inside of a lantern-globe; in providing a separate chamber for the wick; and in the several parts and combinations claimed as new.

The object of my invention is to produce a lantern that shall produce a most perfect light, and which at the same time can be used out of doors without being affected by currents of air or wind.

To enable others skilled in the art to make and use my improvements, I will describe the construction and operation of the same.

The glass globe A is made in any of the known forms, and provided at or near the top with tubular openings or projections R, over or into which the upper ends of the metallic tubes D are placed.

The base of the lantern is made of a vertical band, B, and flange or base-band C. No especial form or configuration of the base is essential, and it may be varied as desired.

In this base, I place at the bottom an air-chamber, E, as shown at fig. 4, and by the dotted lines in fig. 3.

If desired, this chamber may be made to cover the entire base of the lantern, by extending the tubes L through it, but, as ordinarily made, it only extends to the openings for the tubes L, and across the bottom. The tubes L pass through the oil-reservoir, and are open top and bottom, as shown.

The lower ends of the tubes or pipes D enter this chamber, or open into it, and the air which passes into E passes into the chamber or annular space S, which surrounds the tube N, and from this through the burner g, and under the cap or cone K to the flame.

The burner g is fitted to the tube N.

This tube holds the wick, which passes through b, and is filled with oil by means of the small tube e, located near its bottom, which, with the tube d, connects it with the oil-reservoir.

f is simply an additional support for N, but, if desired, it may also be made tubular.

The oil-reservoir is the annular space between the bands O and B, which is covered at the top by the disk or plate M, and at the bottom by P; and, in filling, the oil is poured into the tube N, and from that it passes through e into the reservoir, while the air escapes through the tube d.

e represents the ratchet for operating the wick.

The band B projects sufficiently above the disk M to hold the bottom of the globe in place.

The tubes or pipes D are made of tin or other suitable material, and are firmly attached to the base, as shown.

At their upper ends they connect with the projections R of the globe, so as to be easily detached, and allow the globe to be detached for the purpose of repairs, cleaning, or lighting the lamp, or they may be so attached to the base as to spring off when the band or ring J, or other device for holding them, is removed.

The bail or handle Q is also attached to them, as shown.

The cap or dome is made separate and removable, and is secured in place by means of the hook and pin a, or by any other suitable means, and it is made of two plates F and G.

The plate or cup F is spun or stamped up, as shown, and so attached or supported as to leave large spaces, as shown, for the escape of smoke, &c.

The plate G covers the entire top of the globe, and has no perforations.

Into this plate G I insert tube H, which is about one inch in diameter, and extends downward into the globe about one-third of its length, as shown.

A cap or deflector, I, is suspended beneath the tube H by wires, about the distance of one-half of an inch. When the dome or cover is removed, the tube H is removed with it.

By this method of constructing and arranging the dome and the tube H with its cap I, it will be seen that any air which enters the openings in the cap F will be likely to pass out on the opposite side, instead of passing down the tube H, and that, if by any means any portion of the air should pass down the tube H, it will impinge on the cap or deflector I, which will cause it to pass off laterally, and thus prevent it from affecting the flame.

In operation, the air passes directly into the lantern through the tubes L in sufficient quantities to fill the globe. This ventilation also supplies the necessary air to complete the combustion above the cone of the burner.

The heated air which is below the cone K becomes so far rarified as to ascend and cause a current to flow out of the air-chamber E, and create a pressure in the globe above the lower end of H, which drives or presses a current of air out of the openings R through the tubes D into the air-chamber E, and from that to

the flame. This operation is continuous. Fresh air is supplied by the tubes L, and these may be aided by perforations in the band B, if desired.

Having thus fully described my improvement,

What I claim as new, and desire to secure by Letters Patent, is—

1. The dome or cap, when provided with the tube H, in combination with the globe A, substantially as and for the purposes specified.
2. The cap or deflector I, in combination with the tube H, substantially as described.

3. The combination of the burner g and cone K with the annular space S and air-chamber E, and tubes D, substantially as specified.

4. The tubes L, in combination with the air-chamber E, tubes D, and air-space S, for ventilating the lantern, substantially as described.

WM. WESTLAKE.
